FRED C. T. DANIELS AND WILLIAM H. McCUSAULAND, OF BETHLEHEM, PENNSYLVANIA,
ASSIGNORS TO BETHLEHEM STEEL COMPANY.

CHILL MOLD.

Application filed May 20, 1925, Serial No. 31,517. Renewed August 1, 1927.

Our invention relates to chill molds and particularly to that type of mold section used in the casting of rolls. Heretofore chill molds have been suggested in which the chilling surface, which is in contact with the articles cast therein, is formed of a plurality of segments separated by slots which allow for the uniform expansion and contraction of the mold during the casting operation. 5 The practice has been to fill such slots with refractory material so as to present a smooth interior face to minimize the formation of fins on the surface of the casting.

The refractory material is easily dislodged and must be frequently replaced. Furthermore, the metal at the surface of the article cast in mold opposite the slots solidifies differently from the surface in direct contact with the metal of the mold and results in 10 longitudinally extending portions of the metal which have a different form of crystallization than the remaining metal; and, as such portions usually extend in straight lines, the abrupt change in the crystalline 15 structure at this portion causes initial strains at the surface of the article cast with the development of splits and cracks when such articles are in service. This is particularly 20 so in the case of rolls used in the hot rolling 25 of sheets and the like where the rolls are subjected to severe stresses at the surface 30 due to the expansion and contraction of the roll in a well known manner.

Our invention, therefore, has for its object 35 to provide chill sections for molds for casting rolls and the like which sections are provided with sinusoidal or curved slots in order to hold refractory material to better advantage and in order to so dispose the 40 crystalline structure of a casting that the danger of cracks when the latter is placed in service may be minimized.

The preferred embodiment of the invention 45 is illustrated in the accompanying drawing wherein—

Fig. 1 is a plan view of the mold section;

Fig. 2 is a cross sectional view taken on line II—II of Fig. 1;

Fig. 3 is a partial cross section taken on 50 line III—III of Fig. 2 somewhat enlarged; and,

Fig. 4 is a view of the chilling face of the mold section showing a modification.

Referring to the drawings, 10 designates

a mold section provided with the usual lift- 55 ing trunnions 11.

The inner portion of the mold section, which is in contact with the articles cast therein, is formed by a plurality of separated segments 12 to facilitate expansion 60 and contraction due to temperature changes. The segments are separated from each other by the radial slots 13 and are connected to the annular portion 14 of the mold section. The slots extend into cored openings 15 65 which allow the escape of the gases evolved during the casting of the articles in the mold. The slots 13 are waved in the general longitudinal direction, as shown in Fig. 2, and each preferably has curved portions extending to both sides of a plane, indicated by the line 16, through the axis of the mold.

A filler 17 is inserted in each of the slots 13 so that the face of the mold in contact with the article cast is a smooth continuous 70 surface, thereby preventing the formation of fins on the face of said article. Waving of the slots assists in retaining the fillers 17 in place. Not only are the fillers firmly 75 supported due to the curved formation, but movement thereof is resisted even though the chill section may expand.

The fillers are preferably of asbestos or similar material which is refractory and permeable to gases. Asbestos may be prepared in strip form, and such strips are bent to the required waved formation and placed in position in the flask in which the mold section is cast, and constitute the core members for forming the slots 13. The asbestos 85 strips remain in the slots after the mold section is removed from the flask and constitute the fillers 17.

A further novel feature of our invention 90 is the configuration of the slots with relation to the soft spots usually formed on the surface of the articles cast in molds of this type. These soft spots are due to the fact that the metal at the slots between the segments solidifies differently from that part 100 cast in direct contact with the metal of the mold, which results in there being formed in the cast rolls longitudinally extending portions of metal which have a different form of crystallization from the remaining metal. This results in a difference in the stiffness of the material of rolls; and, if 105 used for rolling sheets, the latter are marked

in a curved manner, and such curved markings are more easily removed in the subsequent rolling in the finishing mill than is the case with straight markings.

5 A further advantage of the curved formation of slots resides in the fact that the material of rolls cast will be disposed to better advantage to resist the formation of cracks in service for the reason that the line of pressure of a roll will never coincide with a longitudinally extending weakened portion but will always cross the softer portions. In other words, a roll so formed has a better average strength.

10 15 While we prefer to have the slots 13 extending in sinuous curves, it will be obvious that such slots may extend as single curves from edge to edge of a section, for example, slots 13' of the latter character are shown 20 in Fig. 4.

25 While we have shown our invention in two forms, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended 30 claims.

We claim:

1. A mold having an inner chill portion

divided by sinuous curves into a plurality of sections.

2. An integral mold having an inner chill 35 portion divided by sinuous curves into a plurality of longitudinal sections, the slits between such sections containing a filler.

3. A one-piece, annular sectional chill 40 mold having an annular series of cast openings extending in an axial direction with respect to the mold and cast slots extending inwardly from the openings for dividing the inner or chill portion of the mold into an annular series of separated segments, 45 said slots extending in sinuous curves in an axial direction.

4. A one-piece, annular sectional chill 50 mold having an annular series of radially disposed oblong cast openings extending axially with respect to the mold and cast slots extending inwardly from the inner 55 ends of the openings for dividing the inner or chill portion of the mold into an annular series of separated segments, said slots extending in sinuous curves in an axial direction.

In testimony whereof I hereunto affix my signature this 14th day of May, 1925.

FRED C. T. DANIELS.

In testimony whereof I hereunto affix my signature this 14th day of May, 1925.

WILLIAM H. McCausland.
